UNITED STATES PATENT OFFICE.

GIUSEPPE J. BAUMSTARK, OF NORTH BERGEN, NEW JERSEY.

LOCK.

1,412,600.

Specification of Letters Patent. Patented Apr. 11, 1922.

Application filed July 14, 1921. Serial No. 484,569.

To all whom it may concern:

Be it known that I, GIUSEPPE J. BAUMSTARK, a citizen of the United States, residing at North Bergen, in the county of Hudson and State of New Jersey, have invented new and useful Improvements in Locks, of which the following is a full, clear, and exact specification.

My invention relates to locks and refers particularly to locks of the pin-tumbler type.

My invention relates to locks having certain peculiarities of construction not found in previous devices of this character and capable of producing new and valuable results.

One object of my invention is a lock in which the revoluble cylinder is made capable of revolution by means of a movement of the pins and drivers in a direction parallel to the movement of key insertion.

Another object of my invention is a lock containing false pins, the movement of which in the direction of key insertion, locks the device.

Another object of my invention is a lock capable of being unlocked by means of a key having bits in angular position with respect to each other.

Another object of my invention is a lock containing a bit chamber in which an inserted key bit is revoluble.

Another object of my invention is a lock in which the key insertion will move a plurality of pins, unlocking the device, without affecting the position of a plurality of false pins, the movement of which would lock the device.

These and other objects of my invention are evident upon a consideration of my drawings and specification.

In a broad way, my invention comprises a casing enclosing a revoluble cylinder, within which are a series of pins operative against a series of drivers, the inward movement of the keys moving the pins and drivers in the same direction as the key movement, the movement unlocking the device.

A modified form of the device of my invention contains a single false pin, or a plurality thereof, which is not affected by the unlocking of the device by the movement of the key, but which, if moved inwardly, will lock the device.

The device of my invention also contains a bit chamber in which one of the wing bits

of a key may be revolved before insertion within the pin chambers.

The device of my invention is operative by means of a key containing a series of bits and pin-engaging members in angular position with respect to each other.

In the accompanying drawings a particular form of the device of my invention is shown as applied to a pad-lock, but it is evident that the mechanism of my invention can be readily applied to other form of locks, as door-locks, snap-locks, &c.

In the accompanying drawings, illustrating modifications of the device of my invention, similar parts are designated by similar numerals:

Figure 1 is a rear end view of one form of the device of my invention.

Figure 2 is a front view of the device.

Figure 3 is a key end view of the device.

Figure 4 is a plan view of a key suitable for use in my device.

Figure 5 is a section through the line 5—5 of Figure 3.

Figure 6 is a section through the line 6—6 80 of Figure 5.

Figure 7 is a section through the line 7—7 of Figure 5.

Figure 8 is a section through the line 8—8 of Figure 7.

Figure 9 is a broken section of a modified form of key with method for its employment.

The particular form of the device of my invention, shown in the accompanying drawings, comprises a shell 10, having the openings 11, 12 and 13. Within the shell 10, and carried thereby, is a revoluble key plate 14, having an elongated opening 15 capable of allowing the passage of a key. Within the casing 10, and in alignment with the opening 13, is a revoluble pin cylinder comprising the cylinder casing 16 and the cylinder 17. The revoluble cylinder 17 has the three spaced projecting lock members 18, 19 and 20 and a series of pin chambers 21, 100 21, 22, 22, 23, 23, 23, 23, the chambers being concentric with, but in a different circumference from, the chambers 21, 21, 22, 22.

The end 24 of the casing 10 has a series of driver chambers 25, 25, 25, in alignment 105 with the pin chambers of the cylinder 17, when the device is in locked position.

Within each driver chamber 25, in alignment with the pin chambers 21, 21, 22, 22, is a driver 26, abutting upon which is a spiral 110

spring 27, maintaining the driver 26 in a position across the jointure line between the revoluble cylinder 17 and the non-revoluble member 24, thus preventing the cylinder 5 from revoluble movement.

Within each pin chamber 21, 21, 22, 22 is a movable pin 28 abuttable upon a driver 26, the length of the pin 28 being such that its movement by means of a key will force 10 it inwardly to a position where the driver 26 will be freed from engagement with the cylinder 17, thus allowing the latter to revolve.

Within each pin chamber 23, 23, 23, 23 15 is a false pin 29, free from engagement with the non-revoluble member 24, when the device is in normal position, and so maintained by a spiral spring 30 abutting upon a shoulder of the pin 29 and affixed 20 to the wall of the chamber 23. If the false pin 29 is forced inwardly, it will be positioned across the jointure line of the cylinder 17 and the member 24, thus preventing the former from revolving, the pin 25 29 returning to its original unlocked position when the force is removed.

The pin chambers decrease slightly in diameter toward the opening 13, in order that the pins may not fall therefrom.

30 A pin 31, carried by the member 24, extends into a chamber 32 within the cylinder 17 and acts as a supporting member for the cylinder.

The cylinder 17 is so positioned as to 35 allow a bit chamber 32 between its extremity and the plate 13, for purposes described later.

A spring 33, abutting upon the cylinder member 19 and the wall of the casing 10, 40 tends to return the cylinder to a locked position when the unlocking force is removed.

A stop pin 34, abutting upon the cylinder member 19, prevents the cylinder from revolving beyond its predetermined locked position.

The end 35 of the cylinder 17 has an elongated opening 36, which can be placed in alignment with the opening 15 of the member 14.

50 Revoluble through the openings 11 and 12 of the casing 10, when the cylinder 17 is revolved, is a split ring 37, having recesses 38 and 39 capable of receiving the members 18 and 20 of the cylinder, the ends 55 of the ring 37 being capable of practical abutment upon the member 19 of the cylinder 17.

A key capable of operating the described device is shown in Figure 4 and comprises 60 a flat shank 40, having the pin-engaging members 41, 41, the shank 40 being extended through the shaft 42 to the flat bit 43, having the pin-engaging members 44, 44, the bit 43 being positioned at right angles to 65 the shank 40.

The operation of the device is as follows, the device being in the locked position shown in Figure 5:—

The key bit 44 is passed through the openings 15 and 36 until it is within the 70 bit chamber 32, and is then revolved 45° until the shank 40 is in alignment with the openings 15 and 36, when the shank 40 is passed therethrough. The key is then passed inwardly, the bit 44 and the shank 75 40 entering the pin chambers 21, 21 and 22, 22 respectively, the further movement of the key causing the pin-engaging members 44, 44 and 41, 41 to abut upon the pins 28, 28, 28 and to force the drivers 26, 26, 26, 80 26 from engagement with the cylinders 17, thus allowing the latter to be revolved by the revoluble movement of the key. As the cylinder 17 revolves, it removes the members 18, 18 and 20 from engagement with 85 the split ring 37, which can then be revolved until the opening thereof is positioned outside of the casing 10, and the lock can be removed from a staple through which the ring has passed. The key can 90 then be removed from the lock, if desired. The cylinder 17 is prevented from returning to its original position by the abutment of the members 18, 19 and 20 upon the closed portion of the ring. 95

When it is desired to lock the device, the ring 37 is revolved until the open portion is returned to its original position, when the spring 33 causes the members 18 and 20 to enter the recesses 38 and 39 of 100 the ring and the member 19 to position itself between the ends of the ring, the stop pin 34 preventing the cylinder from further movement.

It has been found possible to pick locks of 105 the pin-tumbler type by inserting wires, or similar devices through the key opening and forcing the pins inwardly to allow of the revolution of the cylinder. It is evident, upon a consideration of my device, that 110 this is rendered extremely difficult, if not, impossible. If a wire is inserted and either of the pins 29, 29, 29, 29 forced inwardly, the movement will lock the device instead of unlocking it. In order to pick the lock, 115 it is therefore necessary to force the four proper pins inwardly and not to force any one of the other pins inwardly.

The above description has been limited to a flat key, but it is evident that a barrel 120 key may be as readily employed, as is shown in Figure 9. In this modification, the member 31 has been extended and reduced in diameter to allow it to fit within the barrel of the barrel key 45.

A consideration of the device disclosed in the drawings will indicate the impossibility of picking it and, it is evident that, any attempt to force it will still more firmly engage the ring with the locking means. 125 130

It is evident that a plurality of key bits may be employed, that they may be at any angle with respect to each other and the key shank, and that they may have a wide variety of 5 pin-engaging members, thus allowing of an almost indefinite number of key shapes.

I do not limit myself to the particular size, shape, number or arrangement of parts, as shown and described, all of which 10 may be varied without going beyond the scope of my invention as shown, described and claimed.

What I claim is:—

1. In a lock, in combination, a casing, a 15 revolvable cylinder, a plurality of movable pins carried by the cylinder, a plurality of drivers abutting upon the pins and retaining the cylinder in non-revolvable position, means whereby the inward movement of a 20 key will move the pins and drivers in the direction of the key movement, releasing the cylinder into a revolvable position and a plurality of false pins carried by the cylinder, the movement of which, in the direction of 25 the key movement, will lock the cylinder from revolution.

2. In a lock, in combination, a casing, a 30 revolvable cylinder within the casing, a plurality of movable pins carried by the cylinder, a plurality of drivers abutting upon the pins and retaining the cylinder from revolution, a key-bit chamber between the 35 extremities of the pins and the casing capable of permitting the revolution of a key-bit therein and an opening within the casing for the introduction of a key, the elements being so positioned that the inward movement of a key will force the pins and drivers in the direction of the key movement, releasing the cylinder for revolvable movement. 40

3. In a lock, in combination, a casing, a 45 revolvable cylinder within the casing, a plurality of movable pins carried by the cylinder, a plurality of drivers abutting upon the pins and retaining the cylinder from revolution, a key-bit chamber between the 50 extremities of the pins and the casing capable of permitting the revolution of a key-bit therein, an opening within the casing for the introduction of a key, the elements being so positioned that the inward movement of a key will force the pins and drivers in the direction of the key movement, releasing the 55 cylinder for revolvable movement and a plurality of false pins carried by the cylinder, the movement of which, in the direction of the key movement, will lock the cylinder from revolution.

60 4. In a lock, in combination, a casing, a 65 revolvable cylinder within the casing, a plurality of movable pins carried by the cylinder, a plurality of drivers abutting upon the pins and retaining the cylinder from revolution, a key-bit chamber between the

extremities of the pins and the casing capable of permitting the revolution of a key-bit therein, an opening within the casing for the introduction of a key, the elements being so positioned that the inward movement of a 70 key will force the pins and drivers in the direction of the key movement, releasing the cylinder for revolvable movement and resilient means whereby the removal of the key will lock the cylinder from revolution. 75

5. In a lock, in combination, a casing, a revolvable cylinder within the casing, a plurality of movable pins carried by the cylinder, a plurality of drivers abutting upon the pins and retaining the cylinder from 80 revolution, a key-bit chamber between the extremities of the pins and the casing capable of permitting the revolution of a key-bit therein, an opening within the casing for the introduction of a key, the elements being 85 so positioned that the inward movement of a key will force the pins and drivers in the direction of the key movement, releasing the cylinder for revolvable movement, resilient means whereby the removal of the key will 90 lock the cylinder from revolution and a plurality of false pins carried by the cylinder, the movement of which, in the direction of the key movement, will lock the cylinder from revolution. 95

6. In a lock, in combination, a casing, a revolvable cylinder within the casing, a plurality of movable pins carried by the cylinder, a plurality of drivers abutting upon the pins and retaining the cylinder from 100 revolution, a key-bit chamber between the extremities of the pins and the casing capable of permitting the revolution of a key-bit therein, an opening within the casing for the introduction of a key, the elements being 105 so positioned that the inward movement of a key will force the pins and drivers in the direction of the key movement, releasing the cylinder for revolvable movement, resilient means whereby the removal of the key will 110 lock the cylinder from revolution, a plurality of false pins carried by the cylinder, the movement of which, in the direction of the key movement, will lock the cylinder from revolution and resilient means whereby the 115 false pins will be returned to a position to allow of the revolution of the cylinder.

7. In a lock, in combination, a casing, an opening within the casing allowing the introduction of a plurality of key-bits, a chamber between the casing and movable pins allowing the revolution of the introduced bits and the further introduction through the opening of other bits in angular planes to the introduced bits, a revolvable cylinder within 120 the casing, a plurality of movable pins carried by the cylinder, a plurality of drivers abutting upon the pins and retaining the cylinder from revolution and means whereby a key, having bits positioned in planes angu- 125

lar with respect to each other, may be introduced into the casing and force the pins and drivers into a position allowing the revolution of the cylinder.

- 5 8. In a lock, in combination, a casing, an opening within the casing allowing the introduction of a plurality of key-bits, a chamber between the casing and movable pins allowing the revolution of the introduced bits 10 and the further introduction through the opening of other bits in angular planes to the introduced bits, a revolute cylinder within the casing, a plurality of movable pins carried by the cylinder, a plurality of drivers abutting upon the pins and retaining the cylinder from revolution, a plurality of false pins carried by the cylinder, the movement of which will lock the cylinder from revolution and means whereby a key, 15 having bits positioned in planes angular with respect to each other, may be introduced into the casing and force the pins and drivers into a position allowing the revolution of the cylinder.
- 20 9. In a lock, in combination, a casing, an opening within the casing allowing the introduction of a plurality of key-bits, a chamber between the casing and movable pins allowing the revolution of the introduced bits 25 30 and the further introduction through the opening of other bits in angular planes to the introduced bits, a revolute cylinder within the casing, a plurality of movable pins carried by the cylinder, a plurality of drivers abutting upon the pins and retaining the cylinder from revolution and means whereby a key, having bits positioned in planes angular with respect to each other, may be introduced into the casing and force the pins and drivers into a position allowing the revolution of the cylinder.
- 35 40 10. In a lock, in combination, a casing, a revolute cylinder within the casing, a plurality of movable pins carried by the cylinder, a plurality of drivers abutting upon the pins and retaining the cylinder from revolution, a plurality of false pins carried by the cylinder, the movement of which will 45 lock the cylinder from revolution and means whereby a key, having bits positioned in planes angular with respect to each other, may be introduced into the casing and force the pins and drivers in the direction of the key movement allowing the revolution of the cylinder.
- 50 55 11. In a lock, in combination, a casing, a revolute cylinder within the casing, a plurality of movable pins carried by the cylinder, a plurality of drivers abutting upon the pins and retaining the cylinder from revolution, means whereby a key, having bits positioned in planes angular with respect to each other, may be introduced into the casing and force the pins and drivers into a position allowing the revolution of the cylinder.
- 60 65 12. In a lock, in combination, a casing, an opening within the casing allowing the introduction of a plurality of key-bits, a chamber between the casing and movable pins allowing the revolution of the introduced bits 70 75 and the further introduction through the opening of other bits in angular planes to the introduced bits, a revolute cylinder within the casing, a plurality of movable pins carried by the cylinder, a plurality of drivers abutting upon the pins and retaining the cylinder from revolution, a plurality of false pins carried by the cylinder, the movement of which will lock the cylinder from revolution, means whereby a key, having bits positioned in planes angular with respect to each other, may be introduced into the casing and force the pins and drivers into a position allowing the revolution of the cylinder and resilient means whereby the removal of the key will lock the cylinder from revolution.

13. In a lock, in combination, a casing, an opening within the casing allowing the introduction of a plurality of key-bits, a chamber between the casing and movable pins allowing the revolution of the introduced bits 80 and the further introduction through the opening of other bits in angular planes to the introduced bits, a revolute cylinder within the casing, a plurality of movable pins carried by the cylinder, a plurality of drivers abutting upon the pins and retaining the cylinder from revolution, a plurality of false pins carried by the cylinder, the movement of which will lock the cylinder from revolution, means whereby a key, having bits positioned in planes angular with respect to each other, may be introduced into the casing and force the pins and drivers into a position allowing the revolution of the cylinder and resilient means whereby the removal of the key will lock the cylinder from revolution.

14. In a lock, in combination, a casing, a revolute cylinder within the casing, a plurality of movable pins carried by the cylinder, a plurality of drivers abutting upon the pins and retaining the cylinder from revolution, interlocking means carried by the cylinder, a split ring revolute through openings in the casing and capable of locking with the interlocking cylinder means 100 and means whereby the introduction of a key having bits positioned angularly with respect to each other will move the pins and drivers in the direction of the key movement allowing of the revolution of the cylinder and the unlocking of the ring.

15. In a lock, in combination, a casing, a revolute cylinder within the casing, a plurality of movable pins carried by the cylinder, a plurality of drivers abutting upon the pins and retaining the cylinder from revolution, interlocking means carried by the cylinder, a split ring revolute through openings in the casing and capable of locking with the interlocking cylinder means, 110 means whereby the introduction of a key having bits positioned angularly with respect to each other will move the pins and drivers in the direction of the key movement allowing of the revolution of the cylinder and the unlocking of the ring and a plurality of false pins carried by the cylinder, the movement of which, in the direction of the key movement, will lock the cylinder from revolution.

16. In a lock, in combination, a casing, a revolute cylinder within the casing, a plurality of movable pins carried by the cylinder, a plurality of drivers abutting upon the pins and retaining the cylinder from revolution.

- revolution, interlocking means carried by the cylinder, a split ring revoluble through openings in the casing and capable of locking with the interlocking cylinder means; a plurality of false pins carried by the cylinder, the movement of which will lock the cylinder from revolution and means whereby a key having bits positioned angularly with respect to each other, having angularly positioned bits, may be introduced into the casing and force the pins and drivers in the direction of the key movement allowing the revolution of the cylinder.
16. In a lock, in combination, a casing, a revoluble cylinder within the casing, a plurality of movable pins carried by the cylinder, a plurality of drivers abutting upon the pins and retaining the cylinder from revolution, interlocking means carried by the cylinder, a split ring revoluble through openings in the casing and capable of locking with the interlocking cylinder means and a plurality of false pins carried by the cylinder, the movement of which in the direction of the movement of an introduced key will lock the cylinder from revolution.

Signed at New York city in the county of New York and State of New York this 11th day of July, 1921.

GIUSEPPE J. BAUMSTARK.
